ATTORNEY

UNITED STATES PATENT OFFICE.

PAUL A. DINSMOOR, OF LAWRENCE, KANSAS, ASSIGNOR TO THE LAWRENCE PAPER MANUFACTURING COMPANY, OF LAWRENCE, KANSAS, A PARTNERSHIP.

BOX.

Application filed October 23, 1922. Serial No. 596,268.

To all whom it may concern:

Be it known that I, PAUL A. DINSMOOR, a citizen of the United States, residing at Lawrence, in the county of Douglas and

5 State of Kansas, have invented certain new and useful Improvements in Boxes; and I do declare the following to be a full, clear, and exact description of the invention such as will enable others skilled in the art to 10 which it appertains to make and use the same, reference being had to the accompanying drawings, and to the figures of reference marked thereon, which form a part of this specification.

15 This invention relates to boxes and particularly to fiber boxes used for transportation of canned goods although the invention is not necessarily confined to boxes used for any particular purpose.

20 The weakest points on such boxes are where the board has been weakened by scoring it to make the flaps. Therefore, I have provided means for reinforcing the box at the flap connections or scoring. This is accomplished by pasting strips of reinforcing material on the inside walls of the box so that when the flaps are folded into sealing position, the strips will be concealed.

25 There are two very important advantages 30 resulting from the application of the strips on the inside of the box. The first is that the material of which the strips are made is not put under tension. If the strips were put on the outside of the box when the blanks are formed, just as soon as the flaps were folded over the reinforcing strips would be put under tension and there would be a tendency for either the strips to pull away from the box or else to have their

35 fibers weakened to the point of breaking. Second, if the strips are put on the outside of the box, they are weakened by abrasion against other boxes, the floor and side walls of the freight car, during transportation

40 and handling, as well as being subjected to tearing or loosening effect from the causes named, or by sliding the box over the surface on which it rests. These disadvantages are eliminated by placing the strips on the inside of the box. Hence it will be seen that the location of the strips is a very important feature.

The invention will be clearly apparent by reference to the following description

in connection with the accompanying drawings, in which—

Fig. 1 is a perspective view of a box constructed in accordance with my invention, part being broken away to show the floor or bottom flaps.

60 Fig. 2 is a fragmentary, sectional view through a portion of the box, showing how the strips are applied, and

Fig. 3 is a fragmentary view of a box showing a can supported upon the strip.

65 The box can be formed from a blank of ordinary construction. The box in Fig. 1 is shown as consisting of the side walls 1 and 2, the end walls 3 and 4, the side flaps 5 and 6 and the end flaps 7 and 8. Flaps corresponding to 5, 6, 7 and 8 are on the bottom edges of the walls 1, 2, 3 and 4. One end wall is secured to a side wall in any suitable manner but for convenience the fastening is here shown as a pasted strip 70 9 applied in the usual way. Obviously, however, any of the known method of fastening may be substituted for the strip 9. The material of which the box proper is constructed is preferably fiber board, which is corrugated so as to make each liner form a cord or truss, the completed board being in the nature of a truss. In laminated or solid fiber board the bending strength is almost entirely contained in the two outer plies, 75 hence it is important that the inner ply of a solid fiber board be protected, this being possible by the application of the inner strips 10, 11, 12 and 13 applied to the solid fiber board box, the broad result being the 80 same as in the corrugated board.

85 If one of these cords is cut, the box is materially weakened so it is an important feature of my invention that means is provided to prevent the severing or breaking of the 90 cords or corrugations of the box by the chines of the metal cans which are usually shipped in them.

95 The reinforcing strips may be applied at the same time that the plies in solid fiber or the corrugated sheet and the facing sheets in corrugated board are being pasted together; or after the box blanks have been cut, before they have been scored; or if comparatively thin reinforcing strips are used, 100 after the blank has been scored. The reinforcing strips are indicated at 10, 11, 12 and 13 for reinforcing the connections between

the flaps 5, 6, 7 and 8 and the walls 1, 2, 3 and 4. Corner reinforcements 14 may be provided at the respective corners if desired, and when so added, in addition to protecting the box liners against cutting or breaking, these strips applied at the corners increase the tiering strength; that is, to strengthen the box against collapsing when weight is piled on it. I have shown side flaps 5 and 6 and end flaps 7 and 8 at the top of the box, it being obvious that similar flaps are at the bottom of the box and that these flaps are reinforced with corresponding strips.

In Fig. 2 it will be assumed that the side wall 1 carries a side flap 5, the scoring 15 being reinforced by the strip 10. When the strips are put on the inside of the box, the scoring or groove formed at 15 will conform the strip to the box blank. Then as the flaps 20 are bent over to closing position, the bend at the longitudinal center of each strip will be on a relatively short arc so that there will be no stretching or stressing of the fibers of which the strip is composed.

The bottom strip which according to Fig. 3 would correspond to the strip 13, is in Fig. 3 designated 13'. Its lateral portion resting on the bottom of the box will serve as a mat or reinforcement for the chine 16 of the metal can 17 so that it will receive the pressure of the chine and prevent the cords of

the box from becoming broken which would weaken the box. Of course, these lateral portions 18 extend all around the inner corners of the box and along the side walls 35 where the bottom flaps are joined to them so the chine will not rest against the box proper but against the reinforcing.

This is quite an important feature because with these strips arranged as described, the 40 cords cannot be cut or weakened and, therefore, the box will maintain its original strength. Also is it important that the strips be on the inside of the box because when the box is pulled across the floor or counter, 45 the strips will not be torn off as they are protected by the box proper.

It will, therefore, be seen that a box constructed in accordance with my invention can be easily made and reinforced in an 50 efficient manner.

What I claim and desire to secure by Letters-Patent is:

In a corrugated board box, a joint formed by first producing a narrow compressed zone 55 in a corrugated blank, then reinforcing said zone by pasting thereon a thin strip of flexible material wider than the width of said zone.

In testimony whereof I affix my signature.

PAUL A. DINSMOOR.
